TWO TEMPERATURE REFRIGERATION APPARATUS

Leslie B. M. Buchanan, Springfield, Mass., assignor to Westinghouse Electric Corporation, East Pittsburgh, Pa., a corporation of Pennsylvania

Application August 13, 1946, Serial No. 690,158

7 Claims. (Cl. 62—3)

1

This invention relates to refrigeration apparatus of the compressor-condenser-capillary tube-evaporator type, and more especially to a means for distributing the refrigerant circulated by a single compressor to two or more evaporators connected in parallel.

When supplying refrigerant to two evaporators connected in parallel in such a system, a difficulty arises in the proper proportioning of the refrigerant to the two evaporators. It is desirable, for purposes of regulation, to pass a small quantity of refrigerant vapor with the liquid refrigerant from the condenser into the capillary tube during certain conditions of load.

Where a difference in the refrigerant level or in the suction pressure on the two evaporators is to be maintained, a separate capillary tube is used for each evaporator. These tubes are customarily connected to one condenser. In such a system, the problem consists not only in apportioning the refrigerant liquid to the two capillary tubes in the proper ratio but also in apportioning the refrigerant vapor to these tubes. Since the bore of a capillary tube for a domestic refrigerator is about .03 of an inch in diameter, this apportionment is difficult.

It is, accordingly, an object of this invention to provide a novel means for operating two or more evaporators in parallel from a common source of compressed refrigerant vapor while using only capillary tubes as flow-impeding devices.

It is a further object of the invention to utilize a single compressor and capillary tubes for operating two evaporators in parallel.

These and other objects are effected by the invention as will be apparent from the following description and claims taken in connection with the accompanying drawings, forming a part of this application, in which:

Fig. 1 is a schematic drawing of the refrigerating apparatus of this invention; and

Fig. 2 is an enlarged sectional view of the upper portion of the refrigerant compressor of Fig. 1.

Referring to the drawings, the reference numeral 10 designates a reciprocating compressor driven by an electric motor 12. The compressor 10 includes a reciprocating piston 14, a main inlet port 16, an auxiliary inlet port 18 and an exhaust port 20. The compressed vapor from the exhaust port 20 passes through the exhaust valve 22 into the pressure conduit 24 which communicates with the two air-cooled condensers 26 and 28 wherein the refrigerant vapor is condensed into a liquid.

The refrigerant liquid condensed in condenser 28 passes through a capillary impedance tube 30

5 to a low temperature evaporator 32 wherein the refrigerant liquid is vaporized at a low suction pressure and then passes through a suction tube 34 to the main inlet port 16. The refrigerant liquid condensed in the condenser 26 passes through a capillary tube 36 to a higher temperature evaporator 38 in which the refrigerant liquid is vaporized at a higher suction pressure and thereupon passes through a suction tube 40 to the auxiliary inlet port 18.

10 When the piston 14 of the compressor 10 descends from its uppermost position, a suction is created in the cylinder 42 of the compressor 10 and a suction valve 44 opens to admit refrigerant vapor from the suction conduit 34 to the cylinder 42. As the piston 14 uncovers the auxiliary inlet port 18, refrigerant vapor from the higher temperature evaporator 38 is drawn into the cylinder 42 to relieve the low suction pressure therein and valve 44 closes. On the upstroke of the piston 14, the inlet port 18 is covered by the piston 14 and the vapor in the cylinder 42 is forced through the exhaust port 20 into the pressure conduit 24.

15 The low temperature evaporator 32 is enclosed in an insulated cabinet simulated by the dotted lines 46 to form a low temperature compartment such as used for storing frozen foods. The higher temperature evaporator 38 is enclosed by a second insulated cabinet simulated by the dotted lines 48, which provides a higher temperature food storage cabinet for the storage of unfrozen comestibles.

20 The electric motor 12 receives power from the lines 50 through leads 52 and 54. A temperature-controlling switch 56 is located in lead 54 and is actuated through a snap-acting device 58 by the bellows 60. The bellows communicates through a tube 62 with a bulb 64 which contains a volatile fluid and is located in the insulated cabinet 48. The vapor pressure of this fluid is responsive to the temperature of the cabinet 48 and opens and closes the switch 56 to maintain the temperature of the cabinet 48 between predetermined limits, as is well understood in the art.

25 The condenser 26 is cooled by a fan 66 driven by an electric motor 68 which may be connected through a variable speed rheostat 70 to leads 72 to operate in parallel with the motor 12. The condenser 28 is similarly cooled by a fan 72 driven by an electric motor 74 which may be energized through a variable speed regulating rheostat 76 from leads 78 to operate in parallel with the motor 12.

30 The system is preferably so proportioned that

at least towards the end of each period of operation of the compressor, at least one of the condensers retains no refrigerant liquid, the liquid which is being condensed passing immediately into the capillary tube together with a small quantity of refrigerant vapor. If it is now desired to increase the flow of refrigerant liquid to the evaporator associated with this condenser, the flow of cooling air to the condenser is increased, thereby increasing the rate of condensation of the condenser. The additional refrigerant liquid will replace some or all of the refrigerant vapor formerly flowing into the capillary tube and will enter the evaporator.

If the flow of air through the condenser is still further increased, the flow of refrigerant through the capillary tube connected with the condenser also will be still further increased. This is caused by the fact that refrigerant liquid will be present in the condenser during the operating period of the compressor. The liquid will be sub-cooled and will enter the capillary tube at a lower temperature than formerly. This will retard the formation of refrigerant vapor in the capillary tube and thereby allow more refrigerant liquid to flow through it into the evaporator.

The invention has been described in connection with an apparatus having two evaporators operated at different suction pressures by a ported compressor. It is equally applicable to evaporators operated at the same suction pressure in which case the auxiliary port 18 of the compressor would be eliminated and the evaporator 38 would be connected to the suction conduit 34 in parallel with the evaporator 32.

While the invention has been shown in but one form, it will be obvious to those skilled in the art that it is not so limited, but is susceptible of various changes and modifications without departing from the spirit thereof.

What is claimed is:

1. In refrigerating apparatus including refrigerant vapor compressing means and two evaporators connected to the inlet means of said compressing means, the combination with said evaporators of two condensers connected in parallel to the outlet means of said compressing means and two capillary flow-impeding tubes, one of

said tubes conducting refrigerant from only one of said condensers to only one of said evaporators and the other of said tubes conducting refrigerant from only the other of said condensers to only the other of said evaporators.

2. The refrigerating apparatus according to claim 1 including means for varying the refrigerant condensing rate of at least one of said condensers.

3. The refrigerating apparatus defined in claim 1 including means for varying the refrigerant condensing rate of both of said condensers.

4. The refrigerating apparatus defined in claim 1 including means for circulating a cooling medium through each of said condensers and means for varying the rate of flow of the cooling medium through at least one of said condensers.

5. The refrigerating apparatus defined in claim 1 in which at least one of said capillary flow-impeding tubes is of such low impedance that it allows both refrigerant liquid and refrigerant vapor to pass from one of said condensers to one of said evaporators.

6. In refrigerating apparatus including a compressor having a low pressure inlet port, a higher pressure inlet port, and an exhaust port, a first evaporator connected to said low pressure port, a second evaporator connected to said higher pressure port, the combination with said evaporators of a first condenser connected to said exhaust port, a second condenser connected in parallel to said first-named condenser to said exhaust port, a first capillary flow-impeding tube for conducting refrigerant from only said first condenser to only said first evaporator, and a second capillary flow-impeding tube for conducting refrigerant from only said second condenser to only said second evaporator.

7. The refrigerating apparatus defined in claim 4 including means for varying the refrigerant condensing rate of at least one of said condensers, said one condenser being so proportioned that it passes refrigerant liquid and vapor into the capillary tube which conducts refrigerant vapor therefrom.
